EDWARD B. ELLICOTT, OF CHICAGO, ILLINOIS.

APPARATUS FOR TREATING POLES.

Application filed May 8, 1925. Serial No. 28,867.

This invention relates to apparatus for treating timber, more particularly for treating poles and the like with a preservative.

The time required for the treatment, has 5 been cut down from a period of twenty hours to only six hours. This is accomplished by treating each pole individually in a separate container and providing each container with a steam jacket which surrounds that portion 10 of it as contains the preservative fluid. The steam jacket makes the preservative along the active portion, more fluid and thereby permits it to penetrate into the wood more readily.

15 Another feature of the invention is the provision of a novel means to facilitate insertion and removal of poles out of their respective containers. This result is achieved by providing means for swinging the containers out of the vertical position in which they must be placed for treating the poles, into a horizontal position, in which position they may be more easily removed from their containers. By providing the 20 ends of the containers with caps that may be opened and closed, insertion and removal of the pole is permitted and the preservative inlet and drain line is preferably connected in through one of these caps.

25 Another feature is the provision of preservative, pressure and exhaust lines and connections that will permit the swingable movement of the container, and I provide novel apparatus for treating a part only of 30 the pole, as desired.

Still another feature of the present invention is the provision of a battery of containers which may vary in number in accordance with the requirement for each particular case. By this provision any number 40 of poles may be treated simultaneously.

This invention has also certain other features which are highly advantageous; such as simplicity of construction and a comparatively low manufacturing cost, which 45 will become more apparent during the course of the following detailed description taken in connection with the accompanying drawings.

50 In the drawings:—

Fig. 1 is a longitudinal end view of the apparatus taken on line 1—1 of Fig. 2 showing the manner of positioning and making connection to same when a pole is being 55 treated in full lines, and in dotted lines the

position of the container when it is to be inserted or removed; and

Fig. 2 is a front elevational view taken on line 2—2 of Fig. 1 showing the manner of mounting the individual containers when 60 they are to be used in groups or in battery formation.

Referring more particularly to the drawings, the numeral 1 designates the container or tube which is provided at both ends with 65 the air tight caps 2 and 3. Cap 2 is hinged to the container, as shown at 4, and is provided with locking means 5 for securing it tightly to the container after a pole has been inserted therein. Likewise cap 3 is 70 also hingedly connected to the container as indicated at 6, and is also provided with a means 7 for locking it to the container 1 when a pole is to be removed or inserted therein. The bottom cap 2, however, is also 75 provided with an opening into which a pipe 78 may be fitted for supplying the preservative into and draining it out of the container 1. This pipe 78 is provided with a union so that connection may be made thereto as by means of the flexible hose 8, which in turn is connected to a pipe 9, which forms the main preservative supply and outlet pipe. The connections between the pipe 78 of the remaining containers are made by 80 means of the pipe line 79. The pipe 9 may be controlled by a valve 10. A pipe connection is also made to each container which is substantially adjacent the cap 2. This connection is indicated in the drawing by 85 the numeral 11 and is used for connecting the vacuum line 12 to the container, which connection is completed through the use of the flexible hose 13. By means of the T connections 73, the individual pipe connections from each container are connected to 90 each other through the pipe 76. The valve 14 serves to connect the pipe 12 with the exhaust line when the air is to be exhausted out of the container.

A steam jacket 15, which serves to keep the preservative in a fluid condition to permit it to more readily penetrate the wood, is mounted on the container a little above the pipe connection 11. To the upper and lower 95 portions of the steam jacket 15 are fitted the pipe connections 16 and 17 which serve as the inlet and outlet, respectively, for the steam which is circulated through the jacket. The inlet member 16 is connected by means 100 105 110

of a flexible hose 20 to the pipe line 18, the steam supply in which is controlled by the valve 19. The pipe connection 17 is connected in a similar manner by means of the 5 hose 21 to the exhaust steam line 22. A valve 23 may serve to regulate the amount of exhaust steam flowing out through the line 22. A gage 24 may be provided for indicating the height of the preservative 10 fluid in the container, and a thermometer 25 may be mounted on the jacket 15 to indicate the temperature of the oil or other fluid therein. The pipes 74 and 77 serve to connect the separate containers with 15 the inlet and exhaust steam lines by means of pipes 16 and 17 which are connected to the pipes 74 and 77 by means of the ties 71 and 72, respectively. From the foregoing, it will be observed that the structure will 20 be substantially the same no matter how many containers are used. The valves 19, 23, 14 and 10 simultaneously control the fluid medium which passes into or out of each of the separate pieces of apparatus. 25 Hence, any number of such pieces of pole treating apparatus may be set up in the battery formation as shown in Fig. 2 as may be deemed practicable.

Although not necessary, it is preferable 30 to have each container mounted so that its lower portion may be swung into and out of the pit 26. This is accomplished by securing a block member 27 adjacent one wall of the pit 26 and pivotally mounting the 35 container thereon by the mounting means 28. The mounting means may be made either integral with the jacket 15, or it may consist of a separate member which is clamped to the jacket 15 or the container 40 itself, and pivoted to the block member 27, as at 75. The pit 26 is also wide enough to receive the pipe lines and to permit the connections between the individual pieces of pole treating apparatus to be readily made. 45 A suitable frame 29 is provided over the pit, on which may be mounted a drive shaft for swinging the containers. Along the top of this frame also extends a pipe line 30 which is connected to the container 1 by 50 means of the hose member 31. Air under pressure may be admitted into the pipe line 30 from a pipe or conduit 80 having a control valve 38 and at the proper time it flows into the container 1 and serves to force the 55 preserving liquid into the pole under treatment to thoroughly impregnate the pole with the preservative. A connection similar to the one designated by the numeral 31 in Fig. 1 may also be provided for the other 60 containers.

A flexible cable 32 is fastened to a band 33 on the container 1 and is taken up by a suitable pulley 82 on the shaft 34 when power is applied to the drive wheel 35. A 65 block 36 serves as a support means for the

container when it is in the horizontal position. The shaft 34 may be journaled in bearings 83 and the flexible elements 32 may be trained individually over idler sheaves or pulleys 85.

The device operates as follows:—

A piece of timber or pole which has first been treated in the manner described in my co-pending application Serial No. 62,822, filed October 16, 1925 is placed in the container 1 when it is in the horizontal position shown by the dotted lines in Fig. 1. This is done by loosening the locking member 5 and permitting the cap 2 to be swung away from the opening about the hinge 4. 75 When the pole is inserted, the cap is again placed over the opening and secured tightly thereon by means of the locking member 5. The container tube is then swung about the pivot means 28 by means of the flexible cable 32 and the driving member 35 until it reaches the vertical position shown in Fig. 1. The flexible hose connections between the main pipes and their connection with the pipes 74, 76, 77 and 79 permits this swinging movement. Articulated conduit joints or other provisions for doing this are also contemplated. The flexible member 31 may then be connected to the container, but the compressed air supply thereto is shut off by keeping the valve 38 closed. By opening valve 14, the container is directly connected with the exhaust lines which creates a vacuum within it. When the vacuum within the container reaches the desired point, the valve 14 may be closed and the valve 10 is opened so that preservative liquid may now enter the container tube through the hose 8 and the cap 2. The height of the preservative liquid in the container tube may be ascertained by means of the gage 24, and when the desired height or level is reached, the valve 10 is closed. The height of the preservative level is preferably such that the lower or butt ends of the poles only are treated, although it is to be understood that a greater length or even the entire pole may be treated should it for any reason become desirable. 105

The next thing is to apply pressure on the preservative liquid so as to force it into the pole. This is done by opening valve 38 so that compressed air may be admitted into the container through the flexible hose connection 31. At the same time the valves 19 and 20 are opened so that steam may enter the jacket 15 and keep the liquid in a highly fluid condition by heating it, thereby permitting it to be forced into the openings in the wood more readily. After a period of 110 about six hours, the pole will be impregnated with the preservative fluid to the desired depth. The valves 38, 19 and 23 are then shut off and the valve 10 is opened. By 115 opening valve 10 at this time, the preserva- 120 125 130 135

tive liquid in the container will be drained out of it. The flexible hose member 31 is then disconnected from the container, and the container may then be lowered back into 5 its horizontal position, as indicated by the dotted lines in Fig. 1 to permit removing the pole by again opening the cap 2. Removal of the pole from the container may also be had at the opposite end thereof by opening 10 the cap 3.

Although reference has herein been made to a single container, it is to be understood that the same procedure and mode of operation is applicable when a plurality of 15 containers are used in battery formation as shown in Fig. 2.

The pivotal mounting of the container, together with the provision for raising and lowering the container about its pivotal 20 mounting, expedites insertion and removal of the pole or timber and at the same time permits positioning the container vertically with the lower end in the pit adjacent the preservative supply and drain and the steam 25 and exhaust connections. I have also provided connections which will permit this pivotal movement of the container to vertical position for treatment of the pole and to horizontal position for insertion and removal 30 of the pole.

The end caps close off the opposite ends of the container and permit removal or insertion of the pole from either end. The connection of the preservative supply and drain 35 line to the cap which is at the bottom when the container is in vertical position, is advantageous and exposes the inner end of the preservative supply and inlet line when said cap is opened. The surrounding steam or 40 heating fluid jacket maintains the preservative fluid along the portion of the pole being treated and maintains the same properly heated during the treating process.

I do not wish to be limited to the details 45 shown or described.

I claim:

1. In combination, a frame, a hoisting means mounted thereon, a pivotally mounted container, and means connecting said container at a point above its pivotal mounting with said hoisting means for raising said container from a substantially horizontal position to a substantially vertical position.

2. In combination, a frame, a hoisting 55 means mounted thereon, a pivotally mounted container, means connecting said container at a point above its pivotal mounting with said hoisting means, and steam, preservative, and drain connections to said container below its pivotal mounting.

3. In a device of the class described, a sleeve, caps for closing the ends of the sleeve, an external steam jacket on the outside of the sleeve leaving the ends and interior of 60 the sleeve completely unobstructed, and a

pivotal mounting for the sleeve between its ends.

4. In combination, a frame, a hoisting means thereon, a member adjacent the base of said frame at one side thereof, and a receptacle for a pole pivoted on said member, said receptacle being operatively connected to said hoisting means for swinging said receptacle and pole therein from horizontal position to a substantially vertical position 75 and vice versa, the lower end of said receptacle when the frame is at vertical position being adapted to extend below the bottom of said member into a pit adjacent thereto.

5. In combination, a receptacle for a pole, 80 a mounting therefor pivoted thereto and adapted to permit horizontal and vertical movement of said receptacle, and means for admitting a preservative to said receptacle and withdrawing said preservative therefrom, the lower end of said receptacle being 85 adapted to extend below the base of said mounting when said receptacle is in vertical position.

6. In a device of the class described, a 90 sleeve adapted to receive a pole therein, caps for closing the ends of said sleeve, an external steam jacket on the outside of said sleeve, and a pivotal mounting for the sleeve.

7. In combination, a container adapted 95 to receive a pole therein, means for closing the ends of said container after said pole has been received therein, means for admitting a preservative fluid in the lower end of said container, the length of said container being sufficiently great to receive a pole 100 therein which will sink to the bottom of said preservative of its own weight, means for creating a pressure above said fluid in the container, and a support for said container adapted to hold the same in a substantially vertical position during application of the preservative.

8. In combination, an elongated container 105 adapted to receive a pole therein, removable covers for the ends of said container, means for admitting a preservative fluid in the lower end of said container, the length of said container being sufficiently great to receive a pole 110 therein which will sink to the bottom of said preservative of its own weight, means for creating a pressure above said fluid in the container, and a support for said container adapted to hold the same in a substantially vertical position during application of the preservative.

9. In combination, an elongated container 115 adapted to receive a pole therein, means for closing the ends of said container after said pole has been received therein, means for admitting a preservative fluid in the lower end of said container, the length of said container being sufficiently great to receive a pole 120 therein which will sink to the bottom of said preservative of its own weight, and a support for said container adapted to hold the same in a substantially vertical position during application of the preservative.

125

a pivotal mounting for said container for swinging said container from a horizontal position to a vertical position and vice versa.

10. In combination, a container for receiving a timber, means for supporting the container in a plurality of different positions, means for creating a partial vacuum in said container, means for admitting a preservative fluid into said container when it is in a given position, heating means carried by the container for maintaining the preservative

therein in a fluid state to cause same to penetrate the timber in the container, and means for creating a pressure upon the preservative in the container to agitate said preservative, 15 said support for the container including a pivotal mounting located nearer to one end of the container than the other.

In witness whereof, I hereunto subscribe my name this 6th day of May, 1925.

EDWARD B. ELLICOTT.
